US00D521968S

(12) **United States Design Patent** (10) Patent No.: **US D521,968 S**
(45) Date of Patent: **** May 30, 2006**

(54) **PORTABLE TELEPHONE**

(75) Inventors: **Ha-Youl Jung**, Seoul (KR);
Min-Hyouk Lee, Seoul (KR); **Nam-Mi Kim**, Seoul (KR); **Chang-Hwan Hwang**, Seoul (KR)

(73) Assignee: **Samsung Electronics Co., Ltd.**, Kyunggi-do (KR)

(**) Term: **14 Years**

(21) Appl. No.: **29/224,584**

(22) Filed: **Mar. 3, 2005**

(51) LOC (8) Cl. **14-03**

(52) U.S. Cl. **D14/138**

(58) Field of Classification Search D14/137, D14/138, 147-148, 247-248, 144, 341-347; 379/433.01-433.13, 434; D21/517; 455/575.3, 455/566, 575.1; 345/169; 348/376, 14.02

CLAIM

The ornamental design for a portable telephone, as shown and described.

DESCRIPTION

FIG. 1. is a top front perspective view of a portable telephone showing our new design.

FIG. 2. is a front elevational view thereof.

FIG. 3. is a rear elevational view thereof.

FIG. 4. is a left side elevational view thereof.

FIG. 5. is a right side elevational view thereof.

FIG. 6. is a top plan view thereof.

FIG. 7. is a bottom plan view thereof; and,

FIG. 8. is a front elevational view of using state thereof.
